HEAD AND HANDLE FOR TOOTHBRUSH OR THE LIKE

McClellan J. Klepper, R.R. 1, Higginsville, Mo. 64037

Filed Nov. 27, 1970, Ser. No. 26,191

Term of patent 14 years

Int. Cl. D4—02

U.S. Cl. D4—25

FIG. 1. FIG. 5. FIG. 6

FIG. 2.

FIG. 3.

FIG. 4.

FIG. 7.

FIG. 11. FIG. 12.

FIG. 8.

FIG. 9.

FIG. 10.

FIG. 1 is a perspective view of a head and handle structure embodying my design;

FIG. 2 is a top plan view thereof;

FIG. 3 is a side elevational view thereof;

FIG. 4 is a bottom plan view thereof;

FIG. 5 is an end view thereof as viewed from the head end;

FIG. 6 is an end view thereof as viewed from the handle end;

FIG. 7 is a perspective view of a head and handle structure embodying a modification of the design of FIG. 1;

FIG. 8 is a top plan view of the structure of FIG. 7;

FIG. 9 is a side elevational view thereof;

FIG. 10 is a bottom plan view thereof;

FIG. 11 is an end view thereof as viewed from the head end; and

FIG. 12 is an end view thereof as viewed from the handle end.

The broken lines shown in the several views are for illustrative purposes only and form no part of the claimed design.

I claim:

The ornamental design for a head and handle for toothbrush or the like, substantially as shown and described.
